Patented Aug. 15, 1922.

FIG. 1

INVENTOR.

William E. Kelly
BY
b. J. Heinkel
ATTORNEY.

UNITED STATES PATENT OFFICE.

WILLIAM E. KELLY, OF CLEVELAND, OHIO.

PROPELLER ATTACHMENT FOR VEHICLES.

1,425,777.

Specification of Letters Patent. Patented Aug. 15, 1922.

Application filed August 6, 1921. Serial No. 490,399.

To all whom it may concern:

Be it known that I, WILLIAM E. KELLY, a citizen of the United States, residing at Cleveland, county of Cuyahoga, and State of Ohio, have invented a new and useful Propeller Attachment for Vehicles, of which the following is a specification.

My invention relates to means for manually propelling a vehicle.

10 The object of my invention is a simple and efficient propelling means for vehicles generally and for children's vehicles particularly and which means is adapted to be made up as one unit and readily applied to either a new or an existing vehicle, is adjustable to suit the strength or the convenience, or both, of the operator, and can be folded into compact form for shipment.

My invention is exemplified in the following description and is illustrated in the accompanying drawing in which Fig. 1 is a general perspective view of a vehicle with the propeller attachment applied; Fig. 2 is a section on line 2 of Fig. 1; Fig. 3 is a section on line 3 of Fig. 1; Fig. 4 is a modification of the attachment; Fig. 5 is a general perspective view of the attachment of Fig. 1 showing one manner of folding the same for shipment; and Fig. 6 is a partial plan view showing a method of connection to permit freedom of action of the push bar.

Similar reference characters refer to similar parts throughout the views.

The propeller attachment shown in Fig. 35 1 has the fulcrum blocks 10 and 11, both alike, which have the recess 12 to clear the nuts 32, a central opening for the pivot bolts 13 and 14, and the screws 15 by which the blocks 10 and 11 are fastened to the vehicle A.

The operating lever 16 is fulcrumed on the bolt 13, extends upwardly, and has an opening for the pivot bolt 17.

The intermediate lever 18 is fulcrumed on the bolt 14 as shown in Fig. 2 which figure also applies to the bolt 13, extends upwardly, and has a series of openings 30 for the pivot bolts 19 and 20.

The link 21 is located on the inside of 50 the levers 16 and 18, has a series of openings 31 for the bolt 20, and is held in operative connection with these levers by the bolts 17 and 20; a typical joint thereof being shown in Fig. 3. Other joint construction may be used either here or at the fulcrum.

The push bar 22 is located on the outside

of the lever 18 and is held in operative connection therewith by the bolt 19.

The stops 23 are provided to prevent the push bar 22 from moving beyond a vertical 60 plane either forward or backward as the vehicle A is being propelled.

One end of the spring 24 is secured to the push bar 22 near the bolt 19 while the other end thereof is secured to the lever 65 18 near the bolt 20. This spring is secured as stated so that the push bar 22 may be swung around on the bolt 19 for either forward propulsion of the vehicle as shown in full lines, or for backward propulsion as 70 shown in dotted lines. This spring is advantageous to hold the lower end of the push bar to the ground, but may be omitted since the push bar may be held to the ground by its own weight.

75 The series of openings in the lever 18 as well as the link 21 are provided to permit adjustment of the operating lever as well as the push bar to suit the convenience or strength of the operator.

80 A more simple propeller attachment is shown in Fig. 4 wherein the operating lever 16 is fulcrumed on the block 10 as in Fig. 1, but the push bar 22 is operatively connected directly to the lever 16 by the bolt 85 25. In this instance, the lever 16 has a series of openings 26 to provide adjustment.

85 This apparatus can readily be folded into compact form either for shipment as a unit or for convenience when on the vehicle, as 90 shown in Fig. 5 for instance.

95 In order to prevent slippage or wear of the lower end of the push bar 22, a cap 27, of rubber or other suitable material, is applied thereto.

The operation of the attachment shown in Fig. 1 is as follows. The attachment being secured to the vehicle A by the screws 15 and the several elements thereof are substantially in the positions shown in Fig. 1. 100

In order to propel the vehicle forward in the direction of the arrow thereon, the upper end of the lever 16 is moved backward in the direction of the arrow thereon. This movement causes the link 21 to also 105 move in a backward direction and also causes the upper end of the lever 18 to also move in a backward direction. The lower end of the push bar 22 being in contact with the ground as shown and the above movement being continued, the vehicle A will 110 move forward in the direction of the ar-

- row thereon and will continue to so move forward until the bar 22 reaches a position substantially as shown in dot and dash lines where the inclination of the push bar to the ground is such that the lower end of the push bar no longer firmly engages the ground and slips. At this point the lever 16 is brought back to its original position and the operation repeated.
- 10 In order to propel the vehicle backward, the bar 22 is swung around on the pivot bolt 19 until it assumes the position shown in dotted lines in Fig. 1; backward propulsion is then accomplished by the same operation as previously set forth but in opposite direction.

In order to render this attachment adaptable for different speeds of the vehicle, or for different strength of operators, or for convenience of the operator as the inclination of the operating lever for instance, the leverage or the inclination of the operating lever or the push bar or both may be changed by inserting either the bolt 19 or 25 the bolt 20 in one of the respective adjacent openings in these members.

In such an arrangement, the operation of this device is very similar to the rowing of a boat.

30 Various modifications are possible within the spirit and intent of this invention; therefore, without limiting myself to the precise construction shown and described.

I claim:

- 35 1. An apparatus of the character de-

scribed, comprising a fulcrum block adapted to be secured to a vehicle, an operating lever fulcrumed to said fulcrum block, a push bar operatively connected to said operating lever and the lower end thereof 40 adapted to engage the ground, and a spring operatively connected to said push bar to hold the lower end thereof to the ground.

2. An apparatus of the character described, comprising a fulcrum block adapted to be secured to a vehicle, an operating lever fulcrumed to said fulcrum block, a second fulcrum block adapted to be secured to said vehicle, an intermediate lever fulcrumed on said second fulcrum block, a 45 link operatively connecting said operating lever and said intermediate lever, a push bar fulcrumed on said intermediate lever and the lower end thereof adapted to engage the ground, and a spring adapted to hold the 50 lower end of said push bar to the ground.

3. As a new article of manufacture, a propelling attachment for vehicles, comprising fulcrum blocks adapted to be attached to a vehicle, an operating lever fulcrumed 60 to one of said fulcrum blocks, an intermediate lever fulcrumed to the other of said fulcrum blocks, a link operatively connecting said operating lever and said intermediate lever, a push bar fulcrumed to 65 said intermediate lever, and all of said members arranged to fold into compact form when not in use or for shipment.

WM. E. KELLY.
